[57] CLAIM

The ornamental design for a flower pot stand, as shown.

DESCRIPTION

FIG. 1 is a perspective view of a flower pot stand showing my new design;

FIG. 2 is a top view thereof;

FIG. 3 is a left side view thereof, the right side view being a mirror image of FIG. 3;

FIG. 4 is a bottom view thereof;

FIG. 5 is a front view thereof, the rear view being a mirror image of FIG. 5.
